DRESSER WITH CARVED DOORS OR THE LIKE

Joseph E. Adkinson, 3807 Leland St.,
Chevy Chase, Md. 20015

Filed Feb. 4, 1972, Ser. No. 223,821

Term of patent 14 years

Int. Cl. D6—04

U.S. Cl. D6—154

The single figure is a view in perspective showing my design.

The back of the dresser is conventionally flat and the side not pictured is identical to the side shown.

I claim:

The ornamental design for a dresser with carved doors or the like, substantially as shown and described.
